(57) **CLAIM**

The ornamental design for a barcode printer, as shown and described.

DESCRIPTION

FIG. 1 is a front, top and right side perspective view of barcode printer, showing my new design;

FIG. 2 is a front view thereof;

FIG. 3 is rear view thereof;

FIG. 4 is top view thereof;

FIG. 5 is bottom view thereof;

FIG. 6 is right side view thereof; and,

FIG. 7 is left side view thereof.

The broken lines depict environmental subject matter, are for illustration only and form no part of the claimed design.
